STEREO TAPE CARTRIDGE HOLDER FOR CAR VISOR

Louis G. Standard, 3042 Earlmar Drive,
Los Angeles, Calif. 90064

Filed June 6, 1966, Ser. No. 2,572

Term of patent 14 years

(Cl. D14—6)

FIG. 1.

FIG. 2.

FIG. 3.

FIG. 4.

FIG. 5.

FIG. 6.

FIG. 1 is a perspective view of a stereo tape cartridge holder for car visor, the broken line disclosure in FIG. 1 of a car visor, supporting rod and bracket, and stereo tape cartridge in one of the pockets being for illustrative purposes only.

FIG. 2 is a front elevational view thereof;

FIG. 3 is a rear elevational view thereof;

FIG. 4 is a top plan view thereof;

FIG. 5 is a bottom plan view thereof; and,

FIG. 6 is an end elevational view thereof.

I claim:

The ornamental design for a stereo tape cartridge holder for car visor, substantially as shown and described.
